ABSTRACT OF THE DISCLOSURE

A scaffold having an adjustable tubular frame supporting a scaffold board and having adjustment fasteners connected to the tubing for adjusting and mounting a form support.

Large scale scaffolding has heretofore been a complicated and time consuming operation. This invention relates to simple, inexpensive, and efficient scaffold frames which significantly facilitate construction or any other type of work being done on the side of a structure.

Accordingly, a primary object of this invention is to provide a scaffold frame for supporting both a scaffold board and a form support.

Another object of this invention is to provide a scaffold frame which will bear heavy loads with ease.

A further object of this invention is to provide a scaffold frame which is horizontally adjustable and which allows horizontal adjustment of the form support.

The above and other objects of the invention will become apparent to those skilled in the art after a consideration of the following detailed description of the preferred embodiments of this invention taken together with the accompanying drawings in which:

FIG. 1 is a plan view of the scaffold;

FIG. 2 is a sectional view of a scaffold frame taken on lines 2—2 of FIG. 1;

FIG. 3 is a sectional view of a scaffold frame taken on line 3—3 of FIG. 2;

FIG. 4 is a sectional view taken on line 4—4 of FIG. 2;

FIG. 5 is a sectional view taken on line 5—5 of FIG. 2;

FIG. 6 is a perspective view of a scaffold frame and part of the scaffold board;

FIG. 7 is a cross-sectional view of the scaffold frame tubing taken on line 7—7 of FIG. 6;

FIG. 8 is a cross-sectional view of the form support attachment taken on line 8—8 of FIG. 6;

FIG. 9 is a cross-sectional view of the scaffold frame tubing taken on line 9—9 of FIG. 6;

FIG. 10 is an elevational view of a scaffold frame with various adjustment brackets for the form support;

FIG. 11 is a sectional view taken on line 11—11 of FIG. 10;

FIG. 12 is a sectional view taken on line 12—12 of FIG. 10;

FIG. 13 is a sectional view taken on line 13—13 of FIG. 10;

FIG. 14 is a sectional view taken on line 14—14 of FIG. 10; and

FIG. 15 is a sectional view of the seat plate taken on line 15—15 of FIG. 10.

Referring in detail to the drawings, there is illustrated in FIG. 1 a series of scaffold frames 30 mounted against a vertical surface 32 of a structure 34 and supporting a scaffold board 36 and a form 38. As shown in FIGS. 2 through 9, scaffold 30 is comprised of a tubular rectangular frame work having a diagonal tube 40 supporting the rectangular frame consisting of a base tube 42, upright tubes 44 and 46, and upper horizontal tubes 48 and 50 connected at opposite sides of the upper ends of up-

2

right tubes 44 and 46. Scaffold frame 30 is supported by an adjustment rod 52 within base tube 42, adjustment rod 52 being mounted in a seat plate 54 against vertical surface 32. Scaffold 30 may be horizontally positioned about adjustment rod 52 by means of nuts 56, 56. Base tube 42 extends further than upright tube 44 for supporting scaffold board 36 which is secured by means of a vertical fastener 58 extending upward at the end of base tube 42.

10 Extending from the outer sides of upper tubes 48 and 50 are vertical form support fasteners 70 as clearly seen in FIG. 6. An adjustment plate 72, welded to the bottoms of upper tubes 48 and 50, has a slotted aperture 74. A form support 76 is mounted on the upper surfaces of upper tubes 48 and 50 between form support fasteners 70. A bolt 78, as clearly shown in FIG. 8, which is inserted through aperture 74 in order to fasten form support 76, allows horizontal adjustment of form support 76 to the extent of the length of slotted aperture 74. Form support 76 of each scaffold frame 30 supports form 38 and form boundaries 80 for the pouring of cement. Structure 34 may be any type of beam or concrete girder. An I beam is shown in FIGS. 1 and 2 for purposes of illustration. A strap 84 is secured to the top of structure 34 at points 82. Bolt 78 is inserted through strap 84 in order to lock scaffold 30 into position against vertical surface 32. The weight of the construction workers standing on scaffold board 36 and of the cement load is distributed uniformly on bolts 78 and vertical surface 32.

It should be noted that, although FIG. 1 shows form boundaries 80 for the pouring of cement to lay a sidewalk or similar flat structure, scaffold frames 30 may be utilized in supporting various types of forms for constructing almost any type structure that is to be attached to a vertical surface. There are various types of fasteners which may be used to mount form supports 76 to which form 38 is attached. FIGS. 10 through 14 show various embodiments of brackets, which may be built with angle, pipe, channel, or other materials, for mounting form support 76 and form 38. A multiple angular bracket 90 is shown in FIG. 11 mounted on upper tube 50 and having a vertical leg 92 and an upper horizontal leg 94 forming a cavity within which form support 76 is secured. An upper vertical leg 96 extends from upper horizontal leg 94 in order to form the outer perimeter of either form 38 or boundary 80. FIG. 12 shows a bracket 98 similar to bracket 90 in that it forms a cavity in which form support 76 is secured; however, there is no upper vertical leg 96 since this bracket is not located at the edge of the structure which is being constructed. It should be noted that form support 76 is bolted in the same manner as illustrated in FIG. 8. Figures 13 and 14 show a top adjustment plate 100 having a slotted aperture 102 similar to that of the bottom adjustment plate 72 shown in FIG. 8. Beneath adjustment plate 100 is a hollow rectangular cavity wherein form support 76 and any other supporting structure may be inserted in an adjustable bolt mounting as described in connection with FIG. 8.

FIG. 15 is a blown up view of seat plate 54 which is secured against vertical surface 32 for sharing the counterclockwise moment of force of the scaffold 30, the workers, and the cement load with bolt 78. Seat plate 54 has a cylinder extending perpendicular from a flat surface so that adjustment rod 52 may be inserted within the cylinder for affixing the horizontal positioning of scaffold 30 and preventing unwanted movement.

While the preferred embodiments of this invention have been illustrated and described, it will be understood by those skilled in the art that modifications and changes

may be resorted to without departing from the spirit and scope of the invention.

We claim:

1. A scaffold for construction adjacent a vertical structure, comprising:

a plurality of scaffold frames,

a rigid securing element connected between each of said scaffold frames and the vertical structure for supporting each of said scaffold frames, each of said scaffold frames comprising a base tube, a pair of upright members extending from the base tube, and two horizontal members connected between the upper ends of the upright members, each of the horizontal members being connected at opposite sides of the upright members, forming a rectangular frame, and first means comprising an extension of the base tube beyond one of the upright members, a vertical fastener extending from the ends of said extension, a scaffold board mounted between the last-mentioned upright member and said vertical fastener, a plurality of fasteners extending from the top of each of said scaffold frames, and a form support mounted on the upper surfaces of the upper horizontal members and secured by means of said fasteners for supporting a form which is to be utilized in constructing a structure vertically above and horizontally adjacent to said scaffold board where the workmen are standing during construction.

2. The scaffold of claim 1, including second means for horizontally adjusting the distance between said scaffold board and said form support.

3. The scaffold of claim 2, wherein said second means includes a plate secured to the bottom surfaces of the upper horizontal members of said rectangular frame and having a slotted aperture longitudinally aligned with the horizontal space between the two upper horizontal members last-mentioned and includes a bolt inserted through the slotted aperture and fastened to said form support, said bolt being horizontally movable from one end of the slotted aperture to the other.

4. The scaffold of claim 2, wherein said second means includes an adjustment plate positioned above the upper horizontal members of said rectangular frame and having a slotted aperture and including a bolt inserted through the slotted aperture and fastened to said form support

beneath said aperture plate, said bolt being slidably movable from one end of the slotted aperture to the other.

5. The scaffold of claim 1, including third means for horizontally adjusting the distance of the scaffold from the vertical surface to which the structure being constructed is to be added.

6. The scaffold of claim 5, wherein said third means includes a seat plate secured to the vertical surface the scaffold is adjacent to, an adjustment rod mounted with one end thereof within and against said seat plate, said adjustment rod being mounted within the base tube of said rectangular frame, and a nut at each end of the base tube threadedly engaged with said adjustment rod.

7. The scaffold of claim 1, wherein said plurality of fasteners extend vertically from the outer sides of the upper horizontal members for mounting and securing said form support between fasteners of said plurality of fasteners.

8. The scaffold of claim 1, wherein said plurality of fasteners are brackets extending vertically from the surface of one of the upper horizontal members and having an upper horizontal leg for partially covering the top surface of said form support and holding said form support in position on the top surface of said horizontal members.

9. The scaffold of claim 8, wherein one of said brackets is positioned adjacent the outer end of each of said scaffold frames and has an upper vertical leg extending from the edge of said upper horizontal leg directly above the outer end of each of said scaffold frames forming the outer perimeter of the form which is being supported by the form support.
